United States Patent Office

Des. 202,956
Patented Nov. 16, 1965

202,956

DISPLAY CASE OR SIMILAR ARTICLE

Michael C. Freyer, Frederick V. Gondeck, Lester E. Hickox, Thomas E. Kennedy, and Arthur Perez, Niles, Mich., assignors to Clark Equipment Company, a corporation of Michigan

Filed Dec. 24, 1964, Ser. No. 83,148

Term of patent 14 years

(Cl. D80—11)

FIG. 1

The dominant features of the design reside in the portions shown in full lines.

We claim:

The ornamental design for a display case or similar article, as shown and described.
